FIG. 1 is a perspective view of a hydraulic component housing for a hydraulic valve according to an embodiment of the present invention;

FIG. 2 is a first side view of the hydraulic component housing for a hydraulic valve of FIG. 1;

FIG. 3 is a second side view of the hydraulic component housing for a hydraulic valve of FIGS. 1 and 2;

FIG. 4 is a first end view of the hydraulic component housing for a hydraulic valve of FIGS. 1-3;

FIG. 5 is a second end view of the hydraulic component housing for a hydraulic valve of FIGS. 1-4;

FIG. 6 is a top view of the hydraulic component housing for a hydraulic valve of FIGS. 1-5; and,

FIG. 7 is a bottom view of the hydraulic component housing for a hydraulic valve of FIGS. 1-6.

The broken line portions of the FIGS. illustrate unclaimed portions of the design.
